Primary Examiner — Paula Greene(74) *Attorney, Agent, or Firm* — Nath, Goldberg & Meyer;
Jerald L. Meyer; Tiffany A. Johnson(57) **CLAIM**

The ornamental design for a headphone, as shown and described.

DESCRIPTION

FIG. 1 is a perspective view of a communication device showing our new design;

FIG. 2 is a front view thereof, the rear view is a mirror image;

FIG. 3 is a top plan view thereof;

FIG. 4 is a bottom plan view thereof;

FIG. 5 is a right side view thereof, the left side view is a mirror image; and,

FIG. 6 is a front view showing the design in the folded position.

The broken lines shown are included for the purpose of illustrating the unclaimed portions of the article and form no part of the claim.
